CLAIM

The ornamental design for a display screen or portion thereof with animated graphical user interface, as shown and described.

DESCRIPTION

FIG. 1 shows a first image of a display screen or portion thereof with animated graphical user interface showing our new design;

FIG. 2 shows a second image thereof; and,

FIG. 3 shows a third image thereof.

The peripheral dashed broken lines illustrate a display screen or portion thereof and form no part of the claimed design.

The remaining broken lines at the top and bottom of the display screen illustrate portions of a graphical user interface and form no part of the claimed design.

The appearance of the graphical user interface sequentially transitions between the images shown in FIGS. 1-3. The process or period in which one image transitions to another forms no part of the claimed design.

1 Claim, 3 Drawing Sheets
